UNITED STATES PATENT OFFICE

WILSON P. HUNT, OF MOLINE, ILLINOIS

MULTIPLE DRILL APPARATUS

Application filed November 23, 1927. Serial No. 235,177.

My invention has reference to a multiple drill apparatus, and pertains more specially to that class of machines which are employed for drilling a multiplicity of holes in one operation. These devices include a plurality of tool holding members, or spindles, carried in a block, or head, which is capable of receiving a vertical reciprocable movement, to give to the drills the desired operation. It sometimes occurs that it is desired to omit one or more holes from a piece of work, which can only be done by removing the corresponding drills, or disabling some part of the mechanism so that such drills will fail to act. The purpose of the present invention is to provide a simple and effective means, operable while the machine is in movement, for omitting any drill or drills that may be desired from the operation of the machine, without interfering with the action of the remaining tools.

In the drawings;

Fig. 1 is an elevation of that portion of a multiple machine that carries the drill mechanism, with the invention applied thereto.

Fig. 2 is an enlarged detail, partly in section, of one of the spindle controlling devices.

Fig. 3 is an elevation of another form of the device, and

Fig. 4 is a front edge view thereof.

As shown in Fig. 1 the machine is of the compound type, with two sets of drills in parallel relation, and control devices therefor are shown, operable from one side of the machine.

The reference number 1 indicates a portion of a frame, and 2 a carriage such as is usually mounted in machines of the type mentioned, so as to be capable of vertical play. Supported in the carriage is a pair of housings 3 and 4, in which are rotatably mounted shafts 5 and 6, on which are worm drives 7, engaging worm gears 8 on spindles 9 and 10. In the lower ends of said spindles are the usual drills 11, which may be replaced by other similar tools.

On the upper face of the housing 3 is a bracket 12, with which is pivotally connected

crumpled a lever 14, which has a connection at one end with the upper end of a sleeve 15, in which the upper end of the spindle 9 is rotatably supported, so as to be moved upwardly or downwardly by said sleeve. The connection between the lever and sleeve is by means of a slot 16 in the lever and pin 17 in the head of the sleeve passing through the slot, said head being preferably recessed to receive the end of the lever. The end of the lever is provided with a catch 18 for engagement with an off-set on a post 19, supported on the housing 3. The lever is projected rearwardly into an arm 20, the end of which is connected by a coiled spring 21 with a bracket on the housing 3, the tendency of the spring being to urge the lever forwardly, or in the direction of the sleeve 15. Connected with the lever 14 is an arm 22, provided on its end with a knob 23.

During the operation of the tool the catch 18 is engaged with the post 19, as shown in full lines in the drawings, and the upward stress of the drill is met by a ball-bearing apparatus at 24, between the lower end of the sleeve 15 and a shoulder on the spindle 9. If it is desired to put the drill out of action this is accomplished by striking the ball 23 to force the arm 22 and lever 14 rearwardly, releasing the catch 18, and permitting the lever to fly upwardly, as shown in broken lines in Fig. 2, this movement being impelled by the spring 21, the lever carrying with it the spindle 9 and tool therein, to a point where the tool will not operate on the work contained in the machine. In this operation the link 13 rocks outwardly on its pivot, and the necessary movement of the end of the lever 14 with relation to the head of the sleeve 15 is afforded by the slot 16. When it is desired to return the tool to an operating position this is done by pulling the arm 22 downwardly, causing the lever 14 to automatically reengage with the post 19.

Movement may be imparted to the shaft 5 to rotate the same by any known mechanical means, as, for example, by a motor 25 mounted on the carriage 2, and shaft 26 thereof, upon which is fixed a gear-wheel 27, in mesh with a larger gear wheel 29 on the shaft 5.

Pivots supported on the housing 4 is a link 30, upon the upper end of which is pivoted a lever 31, slotted at its end for engagement with a pin 32 in the head of a sleeve 33, carrying the upper end of the spindle 10, with an arrangement similar to that of the sleeve 15, but not shown in detail herein. On the end of the lever 31 is a catch 34, for engagement with a detent on a post 35, mounted on the housing 4. The lever 31 is projected into an arm 36, the end of which is connected by a spring 37 with a hook on the housing 4, and operates to hold the catch 34 in engagement with the detent, as in the former case. Fixed to the lever 31 is an arm 38, projecting in the same general direction as the arm 22, and provided on its end with a knob 39. When the lever 31 is held downwardly, as in Fig. 1, the tool carried by the spindle 10 is held to its work, and the same can be elevated to a point where the tool will be out of operation by pulling out on the arm 38, permitting the lever to move upwardly, under the force of the spring 37. The spindles are permitted vertical movement independently of the gears thereon, by means of a spline on the spindle, as shown at 40 in Fig. 2, and channel 41 in the gear.

It will be understood that the spindles shown and set forth herein and the operating and controlling mechanisms therefor, are parts in series of such devices, arranged for multiple operations. The operating arms 22 and 38 therefor are all directed toward one side of the machine, where the operator is positioned, and convenient for operation from that side. The lever 31 is re-engaged with its detent by rocking the lever downwardly on its pivot, and to disengage the same the arm 38 is given a quick pull outwardly.

In Figs. 3 and 4 is shown a form of the device for use with spindles which are operated by a shaft in substantial alignment therewith, instead of the gearing hereinbefore referred to. In this form 42 indicates a cylindrical housing, in which is vertically movable a sleeve 43, in which is rotatably supported a spindle 43^a. Connected with the upper end of said spindle is an operating shaft 44, by means of a coupling 45. At its upper end the housing 42 is provided with a pair of ears 47, between which is pivoted one end of a hand-lever 48, and at its lower end the sleeve 43 is fitted with a pair of ears 49, between which is pivoted one end of a link 51, by means of a pin 52, the other end of said link having a pivotal connection with the lever 48 as at *a*. Midway its ends said link 51 is provided with a turn-buckle apparatus 53, for adjusting the length of the link.

When the lever 48 is raised, as shown in Fig. 3 in full lines, the sleeve 43 is held in elevated position thereby, also raising the spindle, and holding the tool carried thereby

out of operative position. This movement is assisted by a spring 54, connected at one end with an extension of the pivot of the arm 48 and at the other end with the pivot 52. This also tends to hold the spindle in elevated position. To allow for the upward movement of the spindle 43^a the shaft 44 is provided with a slide arrangement with its connections, as by a telescopic action. When the arm 48 is forced downwardly it moves inwardly toward the sleeve 43, until the pivot *a* is a little beyond a line between the pivot 52 and pivot of said arm, which prevents accidental movement of the arm upwardly, and assists in holding the drill to its work. When it is desired to raise the spindle a slight movement of said arm outwardly will serve to overcome this deadlock, and the arm and connected parts will move upwardly under the impulse of the spring 54.

By either of the mechanisms hereinbefore set forth any individual drill can be disengaged quickly, and while the machine is in operation if desired.

Gearing similar to that shown for driving the shaft 5 may be provided for the shaft 6, a motor 55 being provided therefor at the opposite end of the carriage from the motor 25.

What I claim, and desire to secure by Letters Patent, is:

1. A device of the class described, comprising a frame and carriage movable thereon, a pair of spindle supporting devices oppositely disposed in said carriage capable of independent movement to or from a piece of work and tool-holding spindles supported thereby, spring controlled levers yieldably mounted for movement away from each other and catch mechanism therefor, said levers being operatively connected with the spindle supports, catch devices on said levers and detents therefor on said carriage, and operators' rods connected with said levers and projected in the same general direction for operation from one side of the machine for use in actuating said levers to release the same and cause a retraction of the spindles from a piece of work.

2. In a machine of the class described, comprising a frame, and multiple drill units therein adapted for simultaneous operation and capable of independent retraction from a piece of work contained in said machine, means connected with each of said drill units, for throwing the same out of operation independently of the others, consisting of a lever mechanism rockingly supported operatively connected with the drill unit, and provided with a catch mechanism, a cooperating stationary catch mechanism, a tension device for holding said lever with the catch in engaging position, and an operator's rod attached to said lever, and provided at its end with a knob for imparting a quick movement to said rod and

lever to cause a retraction of said unit from a piece of work.

3. In a device of the class described, a frame, a carriage supported thereby so as to be capable of a vertical reciprocating movement, a plurality of tool spindles supported in said carriage so as to be independently axially movable therein in the same direction in which the carriage moves, spring-impelled levers connected with said spindles, detents carried by said carriage with which said levers are normally engaged, holding said spindles in operative positions, and means connected with said levers for selective release of one or more thereof, to permit retraction of the tool spindle or spindles connected therewith from a piece of work.

In testimony whereof I affix my signature.

WILSON P. HUNT.
